TO STEINER SALES COMPANY, OF SALT LAKE CITY, UTAH, A CORPORATION OF
UTAH.

ROLLER-TOWEL CABINET.

1,426,121.

Specification of Letters Patent. Patented Aug. 15, 1922.

Application filed November 15, 1918. Serial No. 262,658.

To all whom it may concern:

Be it known that I, GEORGE A. STEINER, a citizen of the United States, resident of Salt Lake City, county of Salt Lake, State 5 of Utah, have invented certain new and useful Improvements in Roller-Towel Cabinets, of which the following is a specification.

The object of my invention is to provide a cabinet of simple, inexpensive construction 10 and one which will allow the convenient removal of the roll with the soiled towel thereon and the insertion of the roll with the clean towel.

A further object is to provide a cabinet 15 having a towel feeding means which will smoothly and uniformly feed the clean section of the towel from its roll and wind up the soiled section on its roll without allowing contact between them.

Other objects of the invention will appear 20 from the following detailed description.

The invention consists generally in various constructions and combinations, all as hereinafter described and particularly 25 pointed out in the claims.

In the accompanying drawings forming part of this specification,

Figure 1 is a side elevation of a towel cabinet embodying my invention.

Figure 2 is a sectional view on the line 30 2—2 of Figure 1.

Figure 3 is a sectional view on the line 30 3—3 of Figure 2.

In the drawing, 2 represents the cabinet, 35 made of suitable material, preferably wood, and mounted in any suitable manner in the toilet room, or wherever the cabinet may be placed. The cabinet is open at the top and bottom and has a door 3 in its front wall,

40 held in place by a button 4 and provided with a suitable mirror 5. When this door is opened, convenient access may be had to the interior of the cabinet. The side walls of the cabinet are provided with vertical 45 slots 6 and 7 extending therein to a point near the lower end of the cabinet. In the bottom of these slots I arrange the clean towel roll 8 having the shaft 9 to turn freely within the slots and resting on the lower 50 ends thereof. This roll is preferably covered by a material 10, such as sand paper, which has the function of gripping the towel and preventing it from slipping on the roll.

55 Above the roll 8 I provide a frame 11 in

which rolls 12 and 13 are journaled. These rolls have shafts 14 and 15 fitting within the slots 6 and 7 and slideable therein and at one end a chain connection 16 is provided between the shafts 15 and 14 by means of 60 which the shaft 14 is driven at the same speed as the shaft 15, a dog 17 being mounted between the shafts to prevent backward movement of the drive sprockets and chain. These rolls 12 and 13 are of the same size 65 and each is preferably provided with a roughened surface consisting preferably of sand paper, as described with reference to the roll 8, and a space is provided between the rolls 12 and 13 and they are held at all 70 times in spaced parallel relation and out of contact with each other. One end of the shaft 15 turns in a hub 18 that is slideable in the slot 6 and is secured to one end of the frame 11.

75 The outer end of the hub has a flange 19 thereon provided with a cam groove 20 to receive a lug 21 of a crank arm 22 having a slot 23 to receive the end of the shaft 15. The lug 21 follows the cam groove 20 when 80 the crank is adjusted therein on the shaft and a stop is provided in the groove for checking the movement of the crank at the end of each revolution. I do not show this device or claim it in detail herein, as it is 85 described and claimed in a companion application, Serial No. 213,152, filed Jan. 22, 1918, now matured into Patent No. 1,287,786, dated Dec. 17, 1918.

Above the feed roll 13 is a roll 25 also having a roughened surface and a shaft 26 slideable in the slots 6 and 7. This is the roll on which the soiled towel is wound.

The frame 11 and the roll 12 rest by gravity upon the roll 8 and the toweling wound 90 therein and the roll 25 rest by gravity upon the roll 13 and as the roll 12 is positively driven from the roll 13 it follows that when the shaft 15 is revolved either by the operation of the crank or by the pull of the 95 user on the clean towel that all the rolls will be revolved synchronously through their frictional engagement and the roll 12, positively driven from the roll 13, will feed the clean towel from the roll 8 while the roll 13 100 will revolve the roll 25 to wind up the soiled towel thereon.

In the upper part of the cabinet I prefer to provide a cross bar or small roller 27 over which the towel is carried before engaging 110

the roll 25. This cross bar is so positioned in the cabinet that it will hold the soiled portion of the towel out of contact with the clean towel roll in the bottom of the cabinet, 5 an important feature of this invention being the arrangement of the rolls in such a manner that any contamination of the clean portion of the towel through contact with the soiled portion is positively prevented. The 10 cabinet is therefore clean and sanitary under all conditions.

I may provide a similar roll at the lower end of the cabinet having the same function as the roll 27 at the top and which I will 15 designate by the same reference numeral. This cabinet is extremely simple in construction and provides an inexpensive, convenient means for feeding the clean towel roll and winding the soiled towel roll so 20 that the attendant is only required to lift the rolls out of the slot in the cabinet, place a roll filled with clean toweling in the bottom of the slots, then put the frame containing the two parallel measuring or feed 25 rolls in the slots above the clean towel roll, pass the free end of the clean towel up through the rear of the cabinet, wind up a few turns on the roll at the top, then place this roll in the slots and the cabinet is ready 30 for use. When the towel has been all transferred from the lower or clean towel roll to the upper or soiled towel roll, the rolls are all removed from the slots, the soiled towel taken to the laundry, a clean roll of toweling placed in the bottom of the slots and the 35 operation repeated.

In the use of the above described towel cabinet, I have noted the following advantages. It makes the unwinding of the clean 40 towel and the winding up of the soiled portion thereof more positive. It provides a greater air space between the clean and soiled portions of the toweling that is being used by the customer and therefore is better 45 for sanitary reasons. It also provides a greater distance between the clean and soiled portions, so that the soiled section, which is often twisted, will have a better chance to become straightened before being wound up 50 on the soiled towel roll. The manufacture of the cabinet is cheapened, its size is decreased and the operation is considerably simplified.

I claim as my invention:

55 1. A roller towel cabinet comprising a casing provided with vertical guideways, a clean towel roll slidable in said guideways, a soiled towel roll slidable in said guideways, feed rolls mounted between said towel rolls 60 and slidable in said guideways, said feed rolls being out of contact with each other and having a driving connection between them, said soiled towel roll resting by gravity upon its feed roll and said clean towel 65 feed roll resting by gravity upon the clean

towel roll and being further held thereon by the weight of the other rolls, revolution of said clean towel feed roll unwinding the clean towel from its roll and winding the soiled portion of the towel upon its roll. 70

2. A towel cabinet having guide ways therein, a clean towel roll mounted in said guideways, a soiled towel roll also mounted in said guideways, a frame interposed between said rolls and having freedom of vertical movement, feed rolls journaled in said frame and having a driving connection between them, one of said feed rolls engaging the clean towel and resting by gravity thereon, the other feed roll contacting with the 80 soiled towel roll, revolution of said clean towel feed roll delivering the clean towel from one roll and synchronously winding the soiled towel on the other roll. 75

3. A towel cabinet comprising a casing, a clean towel roll journaled therein, a soiled towel roll also journaled in said casing, feed rolls for said clean and soiled towel rolls respectively and contacting with the towel thereon, said feed rolls being of the same diameter and having a driving connection between them for revolving said clean and soiled towel rolls synchronously, and said feed rolls and soiled towel roll resting by gravity upon said clean towel roll the feed 85 roll for the soiled towel roll being out of contact with the clean towel roll and with the clean portion of the towel. 90

4. A towel cabinet comprising a casing, a clean towel roll journaled therein, a soiled towel roll also journaled in said casing, feed rolls for said clean and soiled towel rolls and contacting with the towel thereon respectively, said feed rolls having a driving connection between them, and means for unwinding the towel from the clean roll and winding up a corresponding length of the towel on said soiled roll, and said feed rolls and soiled towel roll resting by gravity upon said clean towel roll the feed roll for the soiled towel roll contacting only with the soiled portion of the towel and the soiled 100 towel roll, and the feed roll for the clean towel roll contacting only with the clean towel roll and the clean portion of the towel. 110

5. A towel cabinet comprising a casing having vertical guide ways therein, a soiled towel roll and a clean towel roll vertically movable in said guide ways, feed rolls for said soiled and clean towel rolls and mounted to contact therewith respectively, said feed rolls having a driving connection between them for simultaneous operation thereof and of said soiled and clean towel rolls, said cabinet being open at the bottom 115 and a loop of the clean towel depending through and below said opening, and guides in said casing for directing the soiled towel to its roll and preventing contact thereof with the clean portion of the towel, said feed 120 125 130

rolls resting by gravity upon the lower towel roll.

6. A towel cabinet comprising a casing, a clean towel roll in the lower portion of said casing opposite an opening therein through which the user may grasp and pull a clean portion of the towel, a soiled towel roll in the upper portion of said casing to receive the towel as used, feed rolls mounted to contact by gravity with said clean and soiled towel rolls and having a driving connection between them for operating one feed roll, and the soiled towel roll contacting therewith synchronously with the movement of the other towel roll and its feed roll.

7. A towel cabinet comprising a casing having guideways therein, a soiled towel roll and a clean towel roll movable in said guideways, feed rolls for said soiled and clean towel rolls and mounted between said towel rolls to contact therewith respectively, said feed rolls being supported by the lower towel roll and having a driving connection between them for simultaneous operation thereof and of said soiled and clean towel rolls, said cabinet having an opening through which a loop of the towel extends and guides in said casing for directing the soiled towel to its roll and preventing contact thereof with the clean option of the towel.

8. A towel cabinet, comprising a casing, a clean towel roll journaled therein, a soiled towel roll also journaled in said casing, feed rolls for said clean and soiled towel rolls and contacting with the towels thereon respectively, said feed rolls having a driving connection between them and means for unwinding the towel from the clean towel roll and winding up a corresponding length of the towel on said soiled towel roll, the feed roll for the soiled towel roll contacting only with the soiled portion of the towel and the soiled towel roll, and the feed roll for the clean towel roll contacting only with the clean towel roll and the clean portion of the towel, the upper rolls in said cabinet resting by gravity upon the lower rolls therein.

9. A towel cabinet comprising a casing, clean and soiled towel rolls mounted therein, feed rolls for said clean and soiled towel rolls mounted to contact with the towel respectively and out of contact with each other, the upper towel and feed rolls resting by gravity upon the lower roll.

55. 10. A towel cabinet comprising a casing, a clean towel roll in the lower portion of said casing opposite an opening therein through which the user may grasp and pull a clean portion of the towel, a soiled towel roll in the upper portion of said casing to receive the towel as used, feed rolls mounted between said towel rolls to contact by gravity respectively therewith and having a driving connection between them for operating one feed roll and the towel roll contacting there-

with synchronously with the movement of the other towel roll and its feed roll.

11. A towel cabinet comprising a casing, a clean towel roll in the lower portion of said casing opposite an opening therein through which the user may grasp and pull a clean portion of the towel, a soiled towel roll in the upper portion of said casing to receive the towel as used, feed rolls mounted to contact by gravity with said clean and soiled towel rolls and having a driving connection between them for operating one feed roll, and the soiled towel roll contacting therewith synchronously with the movement of the other towel roll and its feed roll, and means preventing contact of the clean portion of the towel with the soiled portion thereof.

12. A towel cabinet comprising a casing, clean and soiled towel rolls mounted therein, said casing having an opening in its lower part through which the user may grasp and pull the clean towel, feed rolls mounted to contact by gravity respectively with said clean and soiled towel rolls, and having a driving connection between them for operating the soiled towel feed roll to wind up the soiled towel synchronously with the pull of the user on the clean portion of the towel to operate its feed roll.

13. A towel cabinet comprising a casing, clean and soiled towel rolls mounted therein, said casing having an opening in its lower part through which the user may grasp and pull the clean towel, feed rolls mounted to contact by gravity respectively with said clean and soiled towel rolls, and having a driving connection between them for operating the soiled towel feed roll to wind up the soiled towel synchronously with the pull of the user on the clean portion of the towel to operate its feed roll, and means preventing contact of the clean portion of the towel with the soiled portion thereof.

14. A towel cabinet comprising a casing having guideways therein, a soiled towel roll and a clean towel roll movable in said guideways, a frame mounted for vertical movement between said rolls, feed rolls mounted in said frame and contacting respectively with said clean towel roll and said soiled towel roll for driving them simultaneously, a driving connection between said feed rolls for simultaneous movement thereof, the loop of towel from the clean towel roll being extended between the roll and the back of the cabinet to the soiled towel roll in the top thereof and a guiding means in the rear of the soiled towel roll and between which and the back of the cabinet the towel is fed.

15. A towel cabinet comprising a casing having guideways therein, a soiled towel roll and a clean towel roll movable in said guideways, feed rolls mounted to contact

respectively with said clean towel roll and said soiled towel roll for driving them simultaneously, a loop of towel from the clean towel roll being extended between said roll 5 and the back of the cabinet to the soiled towel roll, and a guiding means in the rear of the soiled towel roll and between which and the wall of the cabinet the towel is fed.

16. A towel cabinet comprising a casing, 10 a clean towel roll in the lower portion of said casing through which the user may grasp and pull a clean portion of the towel, a soiled towel roll in the upper portion of said casing to receive the towel as used, feed 15 rolls mounted to contact with said clean and soiled towel rolls and having a driving connection between them for operating one feed roll and the towel roll contacting therewith synchronously with the movement of the 20 other towel roll and its feed roll.

17. A towel cabinet comprising a casing, clean and soiled towel rolls mounted therein, feed rolls for contact respectively with the clean and soiled portion of the towel, a driving 25 connection between said feed rolls for simultaneous movement therewith, a loop of the clean towel depending at the front of said casing and extending to the rear of the clean towel roll, and guide means between 30 which and the rear of said casing the soiled portion of the towel is fed and guided to said soiled towel roll.

18. A towel cabinet comprising a casing, a clean towel roll in the lower part of said 35 casing from which a loop of clean towel depends, within reach of the user, a soiled towel roll in the upper part of said casing to which the soiled towel is guided between said clean roll and the rear of said casing, 40 feeding means acted on by one roll and a feeding means for the other roll, said feeding means being inter-gearied to cause the

same amount of surface movement of the rolls, whereby the pull of the user on the clean towel to unwind it from its roll will 45 impart a similar movement to the soiled roll to wind the towel thereon.

19. A towel and holder comprising a lower clean towel roll from which a loop of clean towel depends, within reach of the 50 user, an upper soiled towel roll to which the soiled towel is guided, and feeding means acted on by one roll and a feeding means for the other roll, said feeding means being inter-gearied to cause the same amount of 55 surface movement of the rolls, whereby the pull of the user on the clean towel to unwind it from the roll will impart a similar movement to the soiled roll to wind the towel thereon.

20. A towel holder, comprising a clean towel support from which a loop of clean towel depends and extends within the holder down through its bottom, a soiled towel roll to which the soiled towel is guided, feeding 60 means for the clean and soiled towel separated so as to prevent infection from the soiled to the clean towel, said feeding means having driving connections between them to cause the same amount of surface movement of the towel rolls, whereby the pull of the user on the clean towel to unwind it from the roll will impart a similar movement to the soiled towel roll to wind the towel 65 thereon, and guide means within the holder 70 preventing the soiled portion of the towel from contacting with the clean portion thereof.

In witness whereof I have hereunto set my hand this 8th day of November, 1918. 80
GEORGE A. STEINER.
